[57] CLAIM

The ornamental design for an electrical switch guard, as shown and described.

DESCRIPTION

FIG. 1 is a front, left side and top environmental perspective view of an electrical switch guard showing my new design, with the front cover shown partially broken away for greater clarity;

FIG. 2 is a right side elevational view thereof, the left side elevational view being a mirror image;

FIG. 3 is a front elevational view thereof;

FIG. 4 is a top plan view thereof;

FIG. 5 is a bottom plan view thereof; and,

FIG. 6 is a rear elevational view thereof.

The broken line showing in FIG. 1 representing a toggle electrical switch is for illustrative purposes only and forms no part of the claimed design.
